(57) **CLAIM**

The design for convertible pants, as shown and described.

DESCRIPTION

FIG. 1 is a front, left perspective view of a convertible pants according to my design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof; and,

FIG. 8 is a front, left perspective view thereof, showing a leg of the convertible pants partially converted.

The broken lines shown in the drawings depict portions of the article that form no part of the claimed design.
